CLAIM

The ornamental design for a switch guard, as shown and described.

DESCRIPTION

FIG. 1 is a perspective view of a switch guard showing my new design.

FIG. 2 is a front elevational view of a switch guard showing my new design in the open position. The broken line showing of the switch and switch plate in FIGS. 1 and 2 is included for the purposes of illustrating environmental elements only and forms no part of the claimed design;

FIG. 3 is a front elevational view of a switch guard showing my new design in the closed position;

FIG. 4 is a rear elevational view thereof;

FIG. 5 is a right side elevational view thereof;

FIG. 6 is a left side elevational view thereof;

FIG. 7 is a top plan view thereof; and

FIG. 8 is a bottom plan view thereof.

FIG. 1.

FIG. 3.

FIG. 4.

FIG. 2.

FIG. 5.

FIG. 6.

FIG. 7.

FIG. 8.
